UNITED STATES PATENT OFFICE.

JULIUS D. FRANK AND ADALOR D. HUARD, OF ALPENA, MICHIGAN.

INTERNAL-COMBUSTION ENGINE.

1,103,497.

Specification of Letters Patent. Patented July 14, 1914.

Application filed May 15, 1913. Serial No. 767,915.

To all whom it may concern:

Be it known that we, JULIUS D. FRANK and ADALOR D. HUARD, citizens of the United States, residing at Alpena, in the county of Alpena and State of Michigan, have invented new and useful Improvements in Internal-Combustion Engines, of which the following is a specification.

Our present invention pertains to internal combustion engines such as have water-jackets around their cylinders.

The object of the invention is to provide means calculated to relieve pressure against the wall of the cylinder or the wall of the jacket in the event of the water or other cooling agent employed freezing, and in that way preclude the possibility of the jacket wall bursting.

With the foregoing in mind the invention in all of its details will be fully understood from the following description and claim, when the same are read in connection with the drawings, accompanying and forming part of this specification, in which:

Figure 1 is a vertical cross-section showing our novel relief means as properly applied to an internal combustion engine, some of the parts being illustrated in elevation. Fig. 2 is a horizontal section showing in plan the seat for the relief valve.

Similar numerals of reference designate corresponding parts in all of the views of the drawings.

Surrounding and spaced from the cylinder 1 of the engine is the outer wall 2 of a water-jacket, and integral with and rising from the said wall 2 is a wall 3, preferably circular, having an inwardly and downwardly inclined upper edge 4, which is preferably, though not necessarily, ground in order to form an efficient valve-seat.

Stepped in a socket 5 on the cylinder wall 1, is the lower portion of a stem 6. The upper portion of the said stem is loosely received in a sleeve 7 on a yoke 8, the end portions of which are fixed with respect to the wall 2 in the manner illustrated, or in any other manner compatible with the purpose of our invention.

Movable vertically on the stem 6 is the relief valve 9, on which is an upwardly extending, exteriorly threaded sleeve 10. The said valve is provided with a beveled and preferably ground surface 11, opposed to the valve-seat 4, and on the valve is preferably,

though not necessarily, employed a gasket 12.

Loosely surrounding and movable vertically on the stem 6 and arranged immediately below the sleeve portion of the yoke 8, 60 is an inverted cup 13, and loosely arranged around the stem 6 and above the sleeve 9 is a cup 14. A coiled spring 15 is seated at its ends in the cups 13 and 14, and surrounds the stem 6. The said spring 15 has for its function to yieldingly hold the valve 9 to its seat under normal conditions so as to prevent the escape of water or other cooling agent from the water-jacket or space. The cup 14 is superposed on a nut 16 that is threaded on 70 the sleeve 10 and is designed to be adjusted when it is necessary to increase or lessen the tension of the spring 15.

Under normal conditions the spring 15 will hold the valve 9 to its seat and enable 75 the latter to effectually prevent the escape of water from the water-jacket or space about the cylinder wall 1. When, however, the water in the water-jacket or space tends to expand and freeze, the valve 9 will be 80 moved away from its seat against the action of the spring 15, and because of the relief thus afforded, bursting of the wall 2 or any other part of the engine will be prevented. It will also be noted here that when the pressure in the water-jacket or space is reduced to a sufficient extent, the spring 15 will return the valve 9 to and hold it against its seat for normal use of the engine.

The construction herein illustrated and 90 described constitutes the best practical embodiment of our invention that we have as yet devised. We do not desire, however, to be understood as confining ourselves to the specific construction and relative arrangement of parts, inasmuch as in the future practice of the invention such changes or modifications may be made as fairly fall within the scope of our appended claim.

Having described our invention, what we 100 claim and desire to secure by Letters-Patent, is:

The combination of an engine cylinder, a water-jacket surrounding the same and having an outlet and also having a flange and 105 a valve seat on said flange, a yoke fixed with respect to the jacket and having an apertured upper portion, a stem disposed in said apertured portion of the yoke and connected with the cylinder, a relief valve loosely sur- 110

rounding said stem and having a threaded sleeve, an inverted cup surrounding the stem and disposed under the upper portion of the yoke, a nut threaded on the sleeve of the 5 valve, a cup superposed on said nut, and a spring surrounding the stem and interposed between the two cups.

In testimony whereof we have hereunto

set our hands in presence of two subscribing witnesses.

JULIUS D. FRANK.
ADALOR D. HUARD.
